SAFETY DEVICE FOR MANHOLE COVERS

Charles E. Rego, East Boston, Mass.

Application September 27, 1933, Serial No. 691,162

5 Claims. (Cl. 200—52)

This invention relates to safety devices for manhole covers and particularly for the covers of street manholes in which gases are liable to accumulate and cause an explosion whenever an electric current therein becomes short circuited, the principal object of the present invention being to provide a means for designating in a service station the particular manhole or manholes in which an explosion has occurred.

0 This object is attained by the mechanism illustrated in the accompanying drawing.

For the purposes of illustrating the invention, one preferred form thereof is illustrated in the drawing, this form having been found to give 5 satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawing

Figure 1 represents a plan of a manhole seat 5 and cover therefor.

Figure 2 represents a vertical section of same on line 2,2, on Fig. 1, drawn to an enlarged scale and showing associated therewith a diagram including other manholes, all electrically connected to an annunciator in a service station.

Figure 3 represents an elevation of the casing of a circuit closer, and

Figure 4 represents a vertical section of same on line 4,4, on Fig. 3.

Similar characters indicate like parts throughout the several figures of the drawing.

In the drawing, 10 represents an annular seat having a depression 11 therein to receive a manhole cover 12.

The cover 12 is adapted to close a manhole 13 which has recesses 14 formed in the side wall thereof.

In each one of these recesses 14 is disposed a tubular member 15, the upper end of which is secured to the annular seat 10.

Each tubular member 15 has a partition 16 therein and the lower end of each tubular member 15 is provided with a closure 17.

Above the closure 17 and below the partition 16 is a piston 18 adapted to reciprocate endwise of said tubular member 15.

Between the partition 16 and piston 18 is a helical spring 19 and just beneath each partition 16 is a filling plug 20.

By removing this filling plug 20 the space be-

tween the partition 16 and piston 18 may be filled with alemite or some similar lubricant, this lubricant keeping the spring 19 and piston 18 in workable condition at all times.

The piston 18 is threaded to the lower end of a rod 21 extending upwardly through the partition 16 and having at its upper end a headed nut 22 extending through the cover 12, the head of each nut 22 being disposed in a depression 12x in said cover.

The piston 18 may be adjusted lengthwise of the rod 21 to vary the tension of the spring 19 and then locked in adjusted position by means of the nuts 23, 24.

The closure 17 may be adjusted to vary the 15 downward movement of the rod 21.

Surrounding each tubular member 15 are a plurality of anchors 25 extending outwardly between the bricks forming the walls of the manhole, thereby preventing any upward movement of the tubular member 15, these tubular members 15 having been disposed within the recesses 14 formed in the wall of the manhole.

The recesses 14 are closed by concrete 14x leaving the cylindrical wall to the manhole free from 25 all protuberances extending into the manhole.

This is of some advantage as it prevents any injury to the workmen within the manhole.

One of the tubular members 15 is provided with a switch 26 which may be of any well known 30 construction and includes a movable member 27 in the path of a member 28 secured to the rod 21.

This switch 26 is in an electric circuit 26x provided with a battery 29 and has a signal such as a lamp 30 in the circuit.

Other manholes 13a, 13b, 13c, 13d, 13e, are connected by electric circuits 26a, 26b, 26c, 26d, 26e, to the battery 29 and in these circuits 26a, 26b, 26c, 26d, 26e, are lamps 30a, 30b, 30c, 30d, 30e, all a part of the annunciator 31.

Whenever a switch 26 of either of these circuits 26a, 26b, 26c, 26d, 26e, is closed, a lamp 30a, 30b, 30c, 30d, 30e, will be illuminated and warn attendants in the service station an explosion has occurred in a particular manhole.

The movable member 27 of each switch 26 is pivoted at 27a and extends outwardly through a slot 27b of the casing of the switch 26, fitting said slot with sufficient friction to prevent its accidental movement.

This member 27 is connected to one end of the circuit wire 26x while the other end of the service wire 26x extends to a blade 27c.

The movable member 27 is normally in the position shown in Fig. 4 of the drawing, but when 55

an explosion occurs and the cover 12 is lifted, the member 28 will come into contact with the cam surface of the member 27 and move it about its pivot 27a so that its side face will come into frictional contact with the blade 27c, the friction between the two surfaces being sufficient to retain the member 27 in contact with said blade 27c until forced outwardly into its original position by one of the service men after the 10 pairs have been made.

This can be done by inserting any small object through the hole 27d and moving the member 27 outwardly about its pivot.

When an explosion takes place within either 15 manhole, its cover 12 will be raised from its seat 10 a limited distance, the springs 19 being compressed during this upward movement of the cover 12.

During the lifting of the cover the gas within 20 the manhole will escape and then the springs 19 will return the cover 12 to its normal position.

During the lifting of the cover 12 the member 28 will operate the movable member 27 of a switch 26 and close its electric circuit to the 25 particular signal lamp associated therewith.

The lamps may be located at any convenient point as in a service station.

Preferably the lamps are a part of an annunciator 31 and each lamp on the annunciator 30 is electrically connected with a different manhole safety device.

By means of this construction whenever an explosion occurs in any particular manhole, a warning is given in the service station and the 35 particular manhole in which the explosion occurs is indicated on the annunciator 31.

By this system the service station is warned whenever an explosion occurs and identification is made as to the particular point where the 40 trouble occurs.

By use of this system the service man can quickly get to the point where the trouble has occurred and make the necessary repairs.

When access is desired to the interior of the 45 manhole, the headed nuts 22 threaded to the upper ends of the rods 21 may be removed and the cover 12 displaced from its seat 10.

The cover 12 has laterally extending projections 32 which rest in recesses 33 in the seat 50 10 and when these projections 32 are positioned within the recesses 33 the nuts 22 will always be in register with the rods 21 within the tubular members 15.

The switch 26 is so constructed that, when once 55 closed by the upward movement of the disk 28, it will remain closed until the service men reach the manhole 13 and make the necessary repairs, it being then returned to its normal position by one of said service men.

60 It is believed the operation and many advantages of the invention will be understood readily without further description.

Having thus described my invention, I claim:

1. In combination with an unobstructed manhole located below the surface of a street or the like and in which a man may work; a cover therefor having a level upper face alined with said street surface; an annular seat for said cover; a rod depending from said cover; a piston thereon; a housing for said piston outside the wall of said manhole; a spring coacting with

said piston to retain said cover on its seat; an electric circuit; a normally open switch therefor in the wall of said housing; and means on said rod for closing said switch whenever said piston is raised against the tension of said spring. 5

2. In combination with an unobstructed manhole below the surface of a street or the like and in which a man may work; a manhole cover therefor having a level upper face alined with said street surface and adapted to have only a 10 slight upward movement when an explosion occurs in said manhole; a member secured to and depending from said cover; a normally open switch; means forming an electric circuit including said switch; and means on said member 15 for closing said switch during the upward movement of said member.

3. In combination with an unobstructed manhole below the surface of a street or the like and in which a man may work; a manhole cover 20 therefor having a level upper face alined with said street surface; means for limiting the upward movement of said cover when an explosion occurs in said manhole; an annular seat for said cover; a tubular member depending from said 25 seat; a rod depending from said cover into said tubular member and movable with said cover; a switch actuating block secured to and movable with said rod; means forming an electric circuit for said manhole; and a normally open 30 switch in said circuit positioned in the wall of said tubular member above and extending into the path of movement of said block.

4. In combination with an unobstructed manhole below the surface of a street or the like and in which a man may work; a manhole cover therefor having a level upper face alined with said street surface; means for limiting the upward movement of said cover when an explosion occurs in said manhole; an annular seat for 40 said cover, said cover and seat having alined holes therein; a shouldered nut in said holes; a rod threaded at its upper end to said nut and depending from said cover; a normally open 45 switch; means forming an electric circuit including said switch; and means on said rod for closing said switch during the upward movement of said rod.

5. In combination with an unobstructed manhole below the surface of a street or the like and in which a man may work; a manhole cover therefor having a level upper face alined with said street surface; an annular seat for said cover; a tubular member depending from said seat and having an oil chamber in its lowest 5 end; a rod depending from said cover and extending into said oil chamber; a piston in said chamber secured to said rod and coacting with the oil in said chamber to permit only a slight upward movement to said cover when an explosion occurs in said manhole; a spring between said piston and the upper wall of said chamber for normally retaining said cover on its seat; a switch-actuating block secured to and movable with said rod; means forming an electric circuit for said manhole; and a normally open switch in said circuit positioned in the wall of said tubular member above and extending into the path of movement of said block.

CHARLES E. REGO.
